UNITED STATES PATENT OFFICE.

HERMAN P. ANDRESEN, OF CHICAGO, ILLINOIS, ASSIGNOR OF ONE-HALF TO DAVID J. EVANS,
OF CHICAGO, ILLINOIS.

GRAB-BUCKET.

No. 921,056.

Specification of Letters Patent. Patented May 11, 1908.

Application filed July 30, 1908. Serial No. 446,133.

To all whom it may concern:

Be it known that I, HERMAN P. ANDRESEN, a citizen of the United States, and resident of Chicago, Cook county, Illinois, have invented 5 certain new and useful Improvements in Grab-Buckets, of which the following is a full, true, and exact description.

My invention relates to improvements in grab buckets and has special reference to 10 improvements in buckets of the class which are characterized by mechanisms that are adapted to both positively open and positively close them.

The object of my invention is to provide a 15 powerful wide opening grab bucket that shall be strong and durable; which shall have maximum closing and digging power; which, likewise, shall be provided with powerful and effective opening means of simple construction, and, in which the metal or material shall be distributed in a manner best adapted to the purposes of strength, durability, light weight and low cost.

A further special object of my invention is 25 to so modify the grab bucket described and claimed in Letters Patent No. 870,812 granted to me November 12, 1907, that the same may be operated as a two line grab; in other words, to adapt the bucket for use with 30 the many "two line" equipments or hoisting rigs that are in present use throughout the country.

My invention consists in a grab bucket of 35 substantially the construction and combination of parts hereinafter described and particularly pointed out in the claims.

My invention will be more readily understood by reference to the accompanying drawings forming a part of this specification, 40 and in which:

Figure 1 is a plan view of a grab bucket embodying my invention; Fig. 2 is a vertical section on the line X—X of Fig. 1; Fig. 3 is a somewhat enlarged horizontal section on the line Y—Y of Fig. 2; Fig. 4 is a vertical section on the line Z—Z of Fig. 3; and Figs. 5 45 and 6 are detail views of modified pulley block constructions.

My improved grab bucket is especially 50 adapted for handling coal, ore and other heavy, bulk materials. It usually comprises two scoops or bucket portions, which are adapted to form a single receptacle when their lower or cutting edges are brought together. A differential winding mechanism, 55

usually referred to as a closing mechanism, is arranged between the scoops and is held in a frame to which also, the scoops are attached. The opening mechanism comprises arms which extend from respective scoops and 60 either chains or links connecting said arms for operation by a single hoisting cable, the same operating after the manner of a toggle lever. Another hoisting cable is wound upon a portion of the differential winding 65 mechanism. When the cable first referred to is placed in tension, the bucket is thereby opened and when the second cable is placed in tension, the bucket is closed. When both cables are placed in tension the members of 70 the bucket retain the positions which they have assumed at the instant. The closing cable may be used alone for hoisting the bucket, but as a rule both cables are used for the purpose.

Referring now to the drawings for the details of the construction of that form of my invention which I prefer, it will be seen that the grab bucket comprises three principal members, namely, the frame A and the two 80 halves or scoops B—B. The frame comprises the triangular vertical members, a—a, two pivot shafts, a'—a', connecting the tops of the members, a—a, and a third shaft, a'', which connects the lower ends of the members, a—a and supports the differential winding drum, C. Each scoop, B, is a rigid structure, comprising side plates, b—b, the back plate, b', and a scoop or shovel section, b''. The ends of the shafts, a'—a', project beyond respective plates, a—a, and upon these 85 I pivot the upper ends of respective scoops, B—B. The scoops may either be fastened to their shafts, a', or the shafts may be secured in the frame plates, a—a, or the shafts 90 may be free to rotate with respect to all of these parts. In this form of my bucket the shafts are not subjected to torsion for the purpose of opening the bucket but serve 95 simply as connecting parts of the frame and as pivots between the frame and the scoops. Upon the back and at the top of each scoop 100 is an opening arm, D, composed of two bent plates, d, connected by a part d' and having their ends, d'', riveted to the side plates, b, 105 of the scoop. Chains or links, d''—d'', connected by a link or ring, d', have their ends attached to respective parts, d', of the arms, D. The bent plates or arms serve to join the sides of respective scoops and they also 110

increase the thickness of the side plates of the scoops at the points where they are attached to or bear upon the shafts, $a'-a'$. The arms, D, and the chains or links, 5 constitute the opening mechanism of the bucket and the hoisting or opening cable, E, is attached to the middle ring, link or stirrup, d^4 . When the weight of the bucket is suspended upon this cable it is obvious that the 10 bucket will fall between the ends of the toggle lever made by the two chains, d^3 , and the tendency being to draw the arms, D, into alignment with the chains, the scoops, B, are opened, until the bucket assumes the appearances represented by the dotted lines in 15 Fig. 2.

The differential winding drum, C, clearly shown in Fig. 4 comprises the large drum or sheave, c' , and the two small drums or 20 sheaves, c^2 . These parts are integral and the drums, c^2 , extend into engagement with the frame plates, $a-a$. I prefer that the drum shall be hollow and that the bearings upon the shaft, a^2 , shall be restricted to the ends 25 thereof, adjacent to the plates, $a-a$. The sheave, c' , is preferably grooved or provided with flanges, c^3 , to retain the closing cable, F. As a further means of preventing excessive slackening of the cable, F, and its displacement 30 from the drum, I employ a channeled semi-circular member or cable guide, f. This is a piece of channel iron bent to fit the drum and is supported between the flanges thereof by tie rods, f' , having their upper ends looped 35 around the shafts, $a'-a'$. One or both of the rods may contain a turn buckle, f'' , for adjusting the cable cage or guide, f. This guide or guard, f, which occupies the groove of the drum prevents the entrance thereto 40 of the coal or other material which is being handled and saves the cable from much wear. The closing cable, F, passes upward from the drum, C, around the guide pulley, f^4 , which holds the cable in line with the vertical central axis of the bucket. The pulley, f^3 , is held by a short shaft in the guard plates, f^4-f^4 , secured on the shafts, $a'-a'$. In some cases I employ single line or strand 45 connections between the small winding drums, c^2-c^2 , and the scoops, but for the purpose of multiplying the closing force of the scoops, I usually prefer the chain or cable loops, c^4 , and the pulleys, c^5 , shown herein. These are duplicated on opposite sides of the 50 large drum, c' , that is, a pair of winding chains are provided for each scoop. As shown in Figs. 1, 2 and 3 the pulleys, c^5 , are placed on large shafts, c^6 , in respective scoops. The ends of these shafts extend 55 through the sides, b, of the scoops. Brackets or guards, c^7 , upon the back plates, b', serve to hold the pulleys and chains in place. Each small drum, c^2 , is provided with two lugs, c^8 and c^9 , on opposite sides, to which the 60 chains of the opposite scoops are attached. 65

Midway between the lugs of each drum, c^2 , is a groove, c^{10} , wherein a link, collar or ring, c^{11} , is placed. The ring is preferably made in two halves bolted together as in Fig. 3, and the ring or link is loose on the drum, c^2 . 70 On opposite sides it is provided with chain fastenings, $c^{8'}$ and $c^{9'}$. The chain which is attached to the lug, c^9 , is wound upon the outer end of the drum, c^2 , and passes from the underside of the drum, thence around the 75 pulley and thence to the fastening, $c^{8'}$. The chain, fastened to the lug, c^8 , is wound upon the inner end of the drum, c^2 , and passes from the top thereof to the pulley on the scoop and thence to the fastening, $c^{9'}$, on 80 the link or collar, c^{11} . The chains are of substantially equal length and when the drum is turned in one direction the chains are wound thereon and the scoops are closed together. Opposite movement of the drum unwinds 85 the chains and thus frees the scoops so that they may be opened by the opening mechanism hereinbefore described. It will be observed that the pull of the opposed chains effected through the drum is taken by the 90 ring or link, c^{11} , interposed between the ends of the opposed chains. The ring being loose on the drum freely adjusts itself to the changing angles of the chains and being balanced on the drum operates without friction thereon. By dead ending the chains upon the ring the full advantages of the two to one pulling effort of the chain loops and pulleys are secured. This could also be done by 95 simply connecting the ends of the opposed chains beneath the drum, c^2 , but their connection to the ring or link, c^{11} , is preferred for the reason that the ends of the chains are thus relatively fixed and thereby equal movement of the scoops is insured. In this regard my winding mechanism may be said to 100 comprise and perform the functions of an equalizing mechanism. In constructing buckets of more than ordinary size and capacity I sometimes find it desirable to substitute for the shafts, c^6 , of Figs. 1, 2 and 3 one or the other of the modified forms of the structural framing shown in Figs. 5 and 6. 105

In Fig. 5, $g-g$, represent beams which extend between the sides of the bucket and $g'-g'$ are blocks arranged between these beams and holding the pulleys, c^5 . Obviously these parts comprise a strong and rigid structure capable of withstanding the strain which is put upon the pulleys, c^5 . 110 For somewhat smaller buckets I employ the beam, g^2 , shown in Fig. 6 and pulley blocks, g^3 , the latter being attached to the beam by means of swivels, g^4 , which permit the block the necessary freedom of movement with 115 respect to the cross beam, g^2 .

The operation of the herein described grab bucket is as follows: When the bucket is held suspended by both cables it may be raised and lowered without changing the positions 120

of its members. While suspended it may be opened by slackening the closing cable, F, or by drawing up on the opening cable, E. At such time the weight of the bucket, plus the weight of the load therein, if any, is exerted upon the scoops through the powerful leverage of the toggle chains or links, d^3 , and the arms, D, with the result that the scoops are forced apart or open. In this condition the bucket is dropped upon the material to be excavated and hoisted and thereupon the opening cable is slackened and the closing cable, F, is drawn taught. The drawing out of the cable, F, causes the rotation of the differential winding drum, thus winding the chains on the small drums, c^2 , and powerfully closing the scoops together upon the load.

As hereinbefore explained the chains, d^3 , practically constitute a toggle lever of which, d^4 , is the middle pivot or knee and as the chains may be replaced by links or toggle lever sections, I have hereinbefore and shall hereinafter refer to the same as a toggle lever which joins the arms, D—D, and to the knee of which the closing cable is attached.

As various modifications of my invention will readily suggest themselves to one skilled in the art, I do not confine the same to the specific structures herein shown and described.

Having thus described my invention, I claim as new and desire to secure by Letters Patent:

1. A grab bucket comprising pivotally joined scoops and a frame, in combination with a closing mechanism arranged upon said frame beneath the pivoted ends of said scoops, arms projecting from said scoops, a toggle lever above said scoops and frame and pivotally interposed between said arms, and an opening cable connected to the knee of said toggle lever, substantially as described.

2. A grab bucket comprising a frame, in combination with scoops pivoted thereon, a mechanism carried by said frame for closing said scoops, a closing cable connected with said mechanism, a toggle lever arranged above said scoops and frame and having its ends connected to respective scoops and an opening cable connected with the knee of said toggle lever, substantially as described.

3. A grab bucket comprising a frame, in combination with scoops pivoted thereon, a closing mechanism carried by said frame beneath the pivoted ends of said scoops, a closing cable connected with said mechanism, arms projecting from respective scoops adjacent to the pivots thereof, toggle links joined by a suitable knee and having their ends attached to respective arms in the plane substantially including the vertical axis of the bucket and an opening cable attached to the knee or common pivot of said links, substantially as described.

4. A grab bucket comprising a frame, in

combination with scoops pivoted thereon, the pivots of said scoops being parallel, arms projecting from said scoops adjacent to respective pivots thereof, a chain extending across the top of said frame and scoops and connecting the outer ends of said arms, an opening cable connected with the middle link of said chain, a closing cable and a suitable closing mechanism interposed between said scoops, substantially as described. 75

5. A grab bucket comprising two scoops pivoted at their upper ends, in combination with arms projecting from said scoops, a toggle lever extending across the top of said scoops and joining the ends of said arms, an opening cable attached to the knee or middle pivot of said toggle lever, a closing cable and a suitable differential closing mechanism interposed between said scoops for operation by said closing cable, substantially as described. 85

6. A grab bucket comprising frame members, in combination with parallel shafts or pivots thereon, scoops having their upper ends attached to respective pivots on the frame members, a differential closing mechanism supported by said frame members and joining said scoops, beneath said pivots, bent plates attached to the upper ends of said scoops and forming arms thereon respectively, said arms having their ends in a common plane with the vertical axis of the bucket, a toggle device above the frame and scoops and connecting the ends of said arms, an opening cable connected with said toggle device and a closing cable connected with said closing mechanism, substantially as described. 95

7. A grab bucket comprising a frame, in combination with scoops having their upper ends pivoted thereon, arms projecting from said scoops, a toggle lever arranged above the scoops and connecting said arms, an opening cable attached to the knee of said lever, a differential winding drum arranged in said frame below the pivots of the scoops, a closing cable wound upon the larger part of said differential drum, pulleys upon respective scoops beneath the pivots thereof, winding chains or cables attached to the smaller portion of said drum and passing over respective pulleys and a link connecting the ends of said winding chains or cables, substantially as described. 110

8. A grab bucket comprising a frame, in combination with scoops having their upper ends pivoted thereon, arms projecting from said scoops, a toggle lever arranged above the scoops and connecting said arms, an opening cable attached to the knee of said lever, a differential winding drum arranged in said frame below the pivots of the scoops, a closing cable wound upon the larger part of said differential drum, pulleys upon respective scoops beneath the pivots thereof, 120 125 130

winding chains or cables attached to the smaller portion of said drum and passing over respective pulleys and a link journaled upon said smaller portion of the drum and connecting the ends of said winding chains or cables, substantially as described.

9. A grab bucket comprising a frame, in combination with scoops having their upper ends pivoted thereon, an opening mechanism 10. connected with said scoops, a differential winding drum arranged in the lower part of said frame and composed of a large drum and small drums, a pair of pulleys on each scoop, winding chains or cables having their 15 ends attached to said small drums and passing around respective pulleys, links or collars journaled on said small drums and whereto the dead ends of respective winding chains or cables are attached, substantially 20 as described.

10. A grab bucket comprising scoops and an opening mechanism, in combination with a drum arranged between said scoops, a closing cable wound thereon, a small drum attached to the first mentioned drum, pulleys 25 on said scoops, a link or collar journaled on said small drum and winding chains or cables upon said pulleys, each said cable having one end attached to said link or collar and its 30 other end attached to said small drum, substantially as described.

11. A grab bucket comprising a frame, in combination with scoops pivoted thereon, a suitable opening mechanism, a differential 35 winding drum supported by said frame beneath the pivots of said scoops and composed of two small drums and a centrally positioned large drum, a guide centrally positioned between the tops of the scoops, a 40 closing cable held by said guide and wound

upon said large drum, a link or collar upon each small drum midway of its ends, pulleys on said scoops and winding chains or cables on said pulleys having their ends attached to respective drums and links or collars, substantially as described.

12. In a grab bucket the scoops in combination with a winding drum positioned between said scoops, pulleys on said scoops, a collar on said winding drum, chains passing 50 over said pulleys and having their ends attached to respective sides of said drum and said collar and means for rotating said drum, substantially as described.

13. In a grab basket, pivotally connected 55 scoops, in combination with a differential winding mechanism arranged between said scoops and including a flanged cable drum, a curved cable guard or gage arranged beneath said drum and between the flanges 60 thereof and means for supporting said guard, substantially as described.

14. In a grab bucket, a frame in combination with scoops pivoted thereon, an opening mechanism, a closing mechanism supported by said frame beneath the pivots of 65 the scoops and including a flanged drum, a closing cable wound on said drum, a curved channel conformed to the lower side of said drum and arranged between the flanges 70 thereof and tie rods connecting said frame and channel, substantially as described.

In testimony whereof, I have hereunto set my hand, this 24th day of July, 1908, in the presence of two subscribing witnesses.

HERMAN P. ANDRESEN.
